UNITED STATES PATENT OFFICE.

JAMES R. COVE, OF ARLINGTON HEIGHTS, MASSACHUSETTS, ASSIGNOR TO LEVER BROTHERS COMPANY, OF CAMBRIDGE, MASSACHUSETTS, A CORPORATION OF MAINE.

APPARATUS FOR PRODUCING CURLLED FLAKED SOAP.

Application filed February 5, 1923. Serial No. 616,899.

To all whom it may concern:

Be it known that I, JAMES R. COVE, a citizen of the United States, residing in Arlington Heights, in the county of Middlesex, in the State of Massachusetts, have invented certain new and useful Improvements in Apparatus for Producing Curled Flaked Soap, of which the following is a specification.

10 The invention relates to apparatus for producing curled flaked soap.

Flaked soap is commonly sold at retail in cartons which are automatically filled, weighed and sealed. When the cartons containing the flaked soap leave the packing and weighing machine they are substantially full. The handling of the cartons and the shaking to which they are subjected in transportation cause the soap flakes as heretofore made to be more or less broken up and reduced in size. Sometimes the soap flakes are broken up to such an extent that they pack together more closely than when the cartons are filled. The result is that when 25 a user opens a package she finds that the soap flakes do not fill the carton and she naturally concludes that the package is under weight and that she is not receiving a fair return for her money. Flaked soap being packed and weighed by automatic machinery, the filled cartons all weigh substantially the same and contain the same amount of soap when they leave the weighing machine. This fact is unknown to the ordinary purchaser, who judges the weight by 30 the apparent quantity.

The object of the present invention is to eliminate, as far as practicable, the tendency of the soap flakes to settle in the cartons.

40 The desideratum is to so form the soap flakes that when they are placed in cartons they will remain in substantially the condition in which they left the soap finishing or flaking machine, so that the cartons will reach the user in substantially the condition in which they leave the packing and weighing machine. To the accomplishment of this object, the soap flakes are curled or rolled as they leave the flaking machine. The invention 45 contemplates the production of curled soap flakes whether or not the sheet of soap is cut previously to the curling or rolling operation, but it is considered desirable, for the best results, to cut the soap, as in the man-

55 ner shown in my copending application, Serial No. 597,711, filed October 30, 1922, previous to curling it. The invention is more fully described hereinafter and is particularly pointed out in the appended claims.

60 In the accompanying drawings illustrating the preferred form of the invention, Fig. 1 is a plan (with parts broken away) of the improved apparatus for producing the curled soap flakes; Fig. 2 is an end elevation, partly in section, of the apparatus 65 shown in Fig. 1; Fig. 3 is a transverse section, on an enlarged scale, through the scraper by which the sheet of soap is removed from the finishing roll and by which the soap flakes are curled or rolled; Fig. 4 is a dia- 70 grammatic view of the portion of a sheet of soap cut transversely and longitudinally previous to its removal from the finishing roll; Fig. 5 is an enlarged perspective view of 75 one of the soap flakes before curling; and Fig. 6 is a perspective view of a curled flake.

The apparatus of the invention may be applied to any usual or preferred form of soap machine having a finishing roll over which a sheet of soap is adapted to be fed. 80 The discharge end of such a machine is shown in the drawings. The finishing roll 10 is mounted on the shaft 11 journaled in the side frames 12 of the machine. The finishing roll may be driven from any source 85 of power and travels in the direction indicated by the arrow in Fig. 2. The sheet of soap is removed from the finishing roll by a scraper 14 arranged transversely at the front end of the machine, with its upper or 90 scraping edge 15 set in close proximity to the finishing roll. All these parts (with the exception of the upper end of the scraper) are of common and well known construction 95 and need no further description.

It is assumed for clarity of description and illustration that the sheet of soap is cut before it is scraped from the finishing roll. For this purpose I make use of the arrangement of cutters disclosed and claimed in my 100 said application. The transverse cuts 15 in the sheet of soap are formed by a spiral cutter 16 arranged so as to rest on the traveling sheet of soap and be turned thereby. The spiral cutter 16 is mounted on a shaft 105 17 journaled in the hubs 18 of arms 19 pivotally mounted on the rod 20 which is supported from the brackets 21 secured to the

sides frames 12. The longitudinal cuts 23 in the sheet of soap are formed by a series of disc cutters 24 journaled in brackets 25 loosely supported from a rod 26 secured in the lower ends of the arms 19. As described in said application, the cutters do not entirely cut through the sheet of soap so that it reaches the scraper as a continuous sheet with the transverse and longitudinal cuts in it.

In accordance with the present invention the upper end of the scraper blade 14 is concaved, as at 27, to cause the individual soap flakes 28 to roll or curl up, as shown at 29 in Fig. 6. To secure a close contact between the roll and the cutting edge of the scraper so as to facilitate the curling of the soap flakes, the upper end 30 of the front face of the scraper is ground on an arc having a radius equal to the radius of the roll. The curve of the concavity 27 in the upper end of the scraper is so shaped (having regard to the speed of the roll 10) as to cause the flakes (as cut) to roll or curl up slightly in the form of an arc, which may approximate a semi-circle. To produce a different curl, it is simply necessary to alter the curve of the concavity 27. Inasmuch as the transverse and longitudinal cuts in the sheet of soap practically sever it, except for a very thin film, the scraper has substantially the same effect as though the soap flakes reached it separately and individually. Moreover, the flakes still adhere to the finishing roll when they come in contact with the scraper

and it is the action of the scraper in removing the flakes from the finishing roll that causes them to curl up, as shown in Fig. 6.

Having thus described the invention what I claim as new is:—

1. An apparatus for producing curled soap flakes comprising a roll over which a sheet of soap is adapted to travel, means for making transverse and longitudinal cuts in the sheet of soap and a scraper for removing the cut flakes from the roll, the roll contacting end of said scraper being concaved to cause the soap flakes to curl or roll up.

2. An apparatus for producing curled soap flakes comprising a moving surface on which a sheet of soap is adapted to travel, and a scraper adapted to contact with the traveling surface to remove the sheet of soap therefrom, the contacting end of said scraper being concaved so as to cause the soap to curl or roll up as it is removed from the surface.

3. An apparatus for producing curled soap flakes comprising a moving roll on the surface of which a sheet of soap is adapted to travel, means for making transverse and longitudinal cuts in the sheet of soap, and a scraper for removing the cut soap from the roll, said scraper having a curved part adapted to press against the roll and a concaved part to engage the soap to cause the cut pieces to curl or roll up in the form of an arc as they are removed from the roll.

JAMES R. COVE.
